UNITED STATES PATENT OFFICE.

HENRY L. CANNE, OF DINGMAN TOWNSHIP, PIKE COUNTY, PENNSYLVANIA.

METALLIC BELT.

No. 920,537

Specification of Letters Patent.

Patented May 4, 1909.

Application filed March 23, 1908. Serial No. 422,671.

To all whom it may concern:

Be it known that I, HENRY L. CANNE, a citizen of the United States, and a resident of Dingman township, in the county of Pike and State of Pennsylvania, have invented a new and Improved Metallic Belt, of which the following is a full, clear, and exact description.

The invention relates to metallic belts such as shown and described in the application for Letters Patent of the United States, No. 395,694, filed by me on October 3, 1907.

The object of the present invention is to provide a new and improved metallic belt, for use in power transmission or for use as an over-shoe for vehicle wheels and, for other purposes, the belt being strong and durable and exceedingly flexible in every direction.

The invention consists of novel features and parts and combinations of the same, which will be more fully described herein-after and then pointed out in the claims.

A practical embodiment of the invention is represented in the accompanying drawings forming a part of this specification, in which similar characters of reference indicate corresponding parts in all the views.

Figure 1 is a plan view of the improvement; Fig. 2 is a side elevation of one of the links and the adjacent side rings interlocked with the loops of the links, the side rings being shown in section; Fig. 3 is a side elevation of one of the links having loops bent up for the reception of the interlocking rings; Fig. 4 is a sectional side elevation of the improvement on the line 4—4 of Fig. 1; Fig. 5 is a plan view of a modified form of the improvement; Fig. 6 is a sectional side elevation of the same on the line 6—6 of Fig. 5; and Fig. 7 is a side elevation of another modified form of one of the links.

The metallic belt is provided with a centrally disposed row of links A, each formed with a flat body A', which may be of disk form, as shown in Figs. 1, 2 and 3 or in the form illustrated in Figs. 5 and 6, each body having a plurality of loops A² extending integrally from the peripheral face of the body A', the loops being bent back and terminating in angular lugs A³ adapted to rest on the face of the body A', so as to sustain the ends of the loops A². As shown in Fig. 7, the body G' of the link is provided with integral loops G² bent back and terminating in angular lugs G³ having reduced terminal pins G⁴ ex-

tending into apertures formed in the body G' to hold the loops against movement. The loops A² of adjacent links A are interlocked with rings B, and adjacent links on one side of the row of links A are connected with each other by links C, formed with a flat body C' in the form of a bar, terminating at its ends in loops C² having their free ends C³ in the form of angular lugs resting on the upper face of the body C', so as to sustain the loops C². Each of the rings B is connected by a transversely-extending link D with a ring E, and the several rings E on one side of the belt are connected with each other by links F, as plainly indicated in Fig. 1. The links D and F are similar in construction to the links C connecting the rings B with each other, and hence further description of the detail construction of the links D and F is not deemed necessary.

As shown in Fig. 1, the loops A² of the links A are arranged obliquely, to connect with the rings B connected with each other by the links C, so that an exceedingly strong central portion of the belt is had, and consequently when the belt is used as an over-shoe for a vehicle wheel this central portion practically forms the tread of the wheel. The outermost rings E and their links F and D are adapted to pass up on the side of the tire of the vehicle wheel, to protect the side and to form a means for attaching the belt to the tire by suitable fastening devices passed over the tire at the inner side thereof or fastened to the spokes of the wheel.

The metallic belt shown and described is rendered exceedingly durable and is capable of flexing in every direction, and by sustaining the terminals of the backwardly bent loops, it is evident that the loops are not liable to be crushed flat, and consequently the rings B and E retain at all times their free connection with the loops, thereby maintaining the flexibility of the belt at all times.

The metallic belt shown and described is simple and durable in construction and can be cheaply manufactured.

Having thus described my invention, I claim as new and desire to secure by Letters Patent:

1. A metallic belt provided with rings and links, each link having a body, and a plurality of approximately rectangular loops, integral with the body and engaging adjacent rings, the free ends of the loops being

angular and resting upon the face of the body, whereby the loops are sustained and prevented from closing upon the rings.

2. A metallic belt provided with rings and links, each link being provided with apertures and a plurality of integral loops, said loops having their free ends terminating in pins entering the said apertures.

3. A metallic belt provided with rings and links, each link having an apertured body, and a plurality of integral loops engaging the rings, each loop being bent back and having at its free end an angular lug resting on the body and terminating in a pin entering an aperture of said body.

4. A metallic belt, comprising links having flat bodies and each provided with integral

loops, the ends of which are in engagement with the bodies of the links, a series of rings on opposite sides of the links and engaged by 20 the loops thereof, bar-like links connecting the rings, a second series of rings on opposite sides of the first named series of rings, and bar-like links connecting the last series of rings with each other and with the first 25 named series.

In testimony whereof I have signed my name to this specification in the presence of two subscribing witnesses.

HENRY L. CANNE.
